UNITED STATES PATENT OFFICE.

FRANK JONES, OF SALT LAKE CITY, UTAH, ASSIGNOR, BY MESNE ASSIGNMENTS, OF ONE-HALF TO INLAND ENGINEERING COMPANY, A CORPORATION OF ILLINOIS.

SCREENING AND FEEDING APPARATUS.

Application filed September 7, 1923. Serial No. 661,399.

My invention relates to screening and feeding apparatus and has for its primary object the provision of an improved apparatus of this character, which will facilitate 5 the handling of heavy bulk material, such as ore, coal, gravel, and the like, and which will be especially suitable for use as either a screening or a feeding apparatus or which, if desired, will perform both of these functions with greater efficiency than other apparatus of this general character now in use.

A more specific object of the invention is to provide an apparatus of the above character, having a screen portion made up of a 15 plurality of spaced bars adapted to be moved with relation to each other, so as to agitate the bulk of material as it passes over the bars, and thereby effect an efficient separation of the smaller particles of material 20 from the bulk, and also prevent the particles of material from lodging in the spaces between the bars. In this connection the invention contemplates, as a preferred construction, two or more sets of bars, which 25 are movable both longitudinally and vertically with relation to each other, whereby the movable bars, in addition to effecting an agitation of the material, function to forward the material toward the discharge 30 end of the apparatus.

Another object is to provide, in a feeding apparatus of the above character, a novel and improved screening member in which the elements of the screen member may be 35 readily and conveniently adjusted to vary the size of the screen openings.

A further object is to provide improved means for varying the inclination of the apparatus, so as to control the velocity of 40 the material passing through the apparatus. In this connection the invention contemplates adjusting means which may be adjusted without interrupting the operation of the apparatus, and which will provide a wide 45 range of adjustment, whereby the movement of the material through the apparatus may be so controlled as to maintain a relatively slow uniform movement, or a movement of such velocity as may be desired in 50 connection with the character of work being performed by the apparatus.

The invention has for further objects the novel constructions and arrangement of parts and devices, hereinafter described and claimed, for carrying out the above stated 55 objects, and such other objects as will appear from the following description of the invention.

The invention is illustrated in a preferred embodiment in the accompanying drawings 60 wherein:

Fig. 1 is a side view in elevation of my preferred apparatus, certain parts of which are broken away to illustrate the internal construction. 65

Fig. 2 is a plan view of the construction illustrated in Fig. 1; and

Fig. 3 is a cross section taken on line 3—3 of Fig. 1.

Like characters of reference designate like 70 parts throughout the several figures of the drawings.

The embodiment of the invention shown in the drawings comprises a stationary supporting structure 10, a normally inclined frame 11 pivotally supported on said structure, adjusting mechanism 12 interposed between the said fixed support and the adjustable frame adapted to be manipulated to vary the inclination of the frame, and a plurality of longitudinally extending bars 75 spaced apart and supported on said frame to provide a screen structure designated generally by the reference character 13. 80

The stationary supporting structure 10 85 may be of any suitable construction that will give the desired rigidity. In the drawings, this supporting structure is illustrated as consisting of upright corner members 14 and 15 secured together by means of suitable 90 cross braces 16. This particular form of supporting structure is illustrated only for the purpose of convenience and will in practice be varied to suit existing conditions.

The frame member consists, preferably, of 95 a pair of channel members 17, 17, arranged back to back to provide rigid side members for opposite sides of the apparatus. These side members are secured together by forward and rear cross members 18 and 19. 100

The frame 11 is pivotally connected at its upper end to the stationary supporting struc-

ture 10 by means of gussets 20, 20, secured between the pairs of channel bars 17, 17, at opposite sides of the frame and supported on studs 21, extending through openings in the 5 upper end of corner members 14 of the stationary supporting structure.

The lower end of the frame is adjustably supported at opposite sides on cams 22, 22, so as to be raised or lowered to vary the 10 inclination of the frame and screen structure, and thereby vary the velocity of the material which passes over the screen structure. When the material being handled is of such character that the desired separation of the 15 smaller pieces is readily obtained, the cams 22, 22, are manipulated to increase the inclination of the screen structure. If the material is of such character as to require a longer time to effect entire separation of the 20 smaller particles, or if the apparatus is employed for feeding ore, stone, gravel, or similar material, into other equipment, for example, rollers, crushers, or the like, where it is desired to maintain a slow uniform passage of material to such equipment, the cams 22, 22 are manipulated to elevate the lower 25 end of the frame 11 and thereby elevate the screen structure toward the horizontal, or to such angle as may be found to be necessary 30 to accomplish the desired results.

The cams are arranged to bear against the inner channels 17, 17 adjacent the gussets 23, 23, interposed between said channel members. These gussets function as guides to 35 hold the frame 11 in proper position on the cams. The cams are preferably rigid on a cross shaft 24, and may be manipulated to vary the inclination of the frame and screen structure without interrupting the operation 40 of the movable bars or other associated parts of the apparatus. The means for manipulating the cams 22, 22, consists, preferably, of a worm wheel 25, secured to the shaft 24, a worm 26 mounted on a transverse shaft 27, a 45 hand wheel 29. The transverse shaft is journaled in suitable bearings 28 on the upright members of the stationary support at one side of the apparatus, and the hand wheel 29 is so disposed that it may be rotated at 50 will to effect the desired adjustment of the frame 11 and screen bar members.

The screen structure of the apparatus is made up, preferably, of two sets of bars designated 30 and 31, arranged in alternate relation to each other, and spaced apart to provide spaces of suitable width between them. The bars of each set are formed near their ends with bosses 32, 32^a, which are formed with recesses 33 adapted to receive 55 the upper ends of rocker arms so as to be supported on said arms with capacity for an oscillatory movement. The bars 30 are supported upon the rocker arms 34, 34^a and the bars 31 are supported on like rocker arms 35, 35^a. The rocker arms and the bars support-

ed thereby are operatively attached to each other by means of pins 36 which are made, preferably, of some suitable low friction metal. The arms 34, 34^a, are fixed to rocker shafts 37, 37^a, mounted in suitable bearings 38, 38^a, on the frame 11. The outer end of shafts 37, 37^a are provided at one side of the apparatus with operating levers 39, 39^a which are connected at equal distances from the center of the shaft 37, 37^a, by means of a connecting rod 40. The operating lever 39^a is somewhat longer than lever 39 and is operatively connected by means of a rod 41 to an eccentric 42. The eccentric 42 is preferably fixed to a transverse shaft 43 journaled in bearings 44 secured to the upper end of the frame 11. The shaft 43, and accordingly the eccentric 42, are rotated by means of a suitable pulley and belt connection 45.

The rocker arms 35, 35^a on which the bars 31 are supported are secured to shafts 46, 46^a, journaled in bearings 47, 47^a. These shafts 46, 46^a are provided with operating levers 48, 48^a, preferably of the same construction as levers 39, 39^a, previously described.

The levers 48, 48^a are connected to each other by means of a connecting rod 49. The extremity of the lever 48^a is operatively connected to an eccentric 50 on shaft 43 by means of an operating rod 51.

The rocking arms 34, 34^a, and 35, 35^a, are preferably secured on their respective shafts with capacity for adjustment longitudinally of the shafts, so that the size of the spaces between the bars 30, 31, may be varied to suit the character of material handled by the apparatus.

In order to make it possible to conveniently adjust the rocker arms to the desired position without danger of disturbing their alignment on their shafts, and to also provide a reliable connection therewith, the shafts are provided with spline keys 52 which fit in suitable key-ways, formed in the hub portions of the rocker arms. These arms are held in their adjusted position by means of set screws 54.

Movement is imparted to each set of the bars 30, 31, by means of their operative connection with eccentrics 42, 50. These eccentrics are preferably arranged so that the extreme position of one is 180° from the corresponding extreme position of the other. This arrangement of the eccentrics, together with the rocking movements of the arms 34, 34^a, and 35, 35^a, imparts an alternate raising and lowering movement of each set of bars simultaneously with a forward and rearward movement thereof. These combined movements of the bars keep the material in agitation as it passes over them, and thereby effect a rapid separation of the small particles from the bulk of material, and at the same time impart a forwarding

movement to the material in the direction of the discharge end of the apparatus.

On each side of the bars are skirt boards 55, 55, provided on their inner faces with 5 wearing strips 56 and attached to the frame 11 with capacity for lateral adjustment so as to vary the space between the outer bars and the skirts in accordance with the size of the spaces between the bars.

10 The adjustable supporting means for the skirts 55, 55, consists preferably of brackets 57 formed at their lower ends with angularly disposed portions 58 provided with elongated openings 59 which receive clamping 15 bolts 60.

The range of adjustment of the skirt boards may, obviously, be made to suit the condition of the material intended to be handled by the apparatus.

20 61 designates an angular apron secured to the stationary frame structure at the discharge end of the apparatus so that the finer particles passing through the bars will be directed under the frame structure and so 25 that the coarser particles passed through the apparatus will be directed away from said stationary frame.

In operation the material to be screened or otherwise treated is introduced into the 30 apparatus at the upper end thereof, and normally slides by gravity over the inclined bars 30, 31, which are operated to keep the portion of material near these bars in agitation, so as to expedite the separation of the 35 smaller particles from the body of material, and to prevent the particles of material from lodging in the spaces between the bars. By the manipulation of the hand wheel 29, the screen bars and pivoted frame member 40 11 may be elevated to any desired angular position such as may be desired in effecting a thorough separation of the small particles from certain kinds of material, or when it is desired to feed the coarse material in uniform 45 manner into other equipment for further treatment.

While the invention is illustrated in one specific embodiment, it will be obvious that the construction illustrated is capable of 50 being modified in various respects without departure from the spirit of the invention.

It will, therefore, be understood that the invention contemplates all such changes as come within the scope of the appended 55 claims.

I claim:

1. In apparatus of the character described, the combination with a fixed supporting structure, of a frame pivoted to said 60 supporting structure and adapted to assume various inclined positions, means for raising and lowering the lower end of said frame, a screen structure on said frame made up of a plurality of longitudinally extending bars, 65 means for adjusting said bars laterally with

respect to each other to vary the size of the spaces between them, means for imparting longitudinal movement to said bars, and laterally adjustable side skirts supported on opposite sides of said screen structure. 70

2. In apparatus of the character described, the combination with a fixed supporting structure, of a frame pivoted to said supporting structure and adapted to assume various inclined positions, means for raising and lowering the lower end of said frame, and a movable screen structure on said frame made up of a plurality of longitudinally extending bars having means for lateral adjustment to vary the size of the 75 spaces between them, and provided on their under surfaces with recesses, rocker shafts at opposite ends of the apparatus, rocker arms secured in alignment on said shafts and adapted to fit at their upper ends in 80 the recesses of said bars, and friction pins for connecting the rocker arms with said bars, crank arms on said rocker shafts, connecting rods connecting said crank arms, and eccentrics operable to impart rocking 85 movements to said rocker arms, whereby said bars receive simultaneous vertical and longitudinal movement, certain of said bars being operated in one direction and certain other of said bars being operated in the opposite 90 direction. 95

3. In apparatus of the character described, the combination with a fixed supporting structure, of a frame pivoted to said supporting structure and adapted to assume various inclined positions, means for raising and lowering the lower end of said frame, and a screen structure on said frame made up of two sets of longitudinally extending bars disposed in alternate arrangement across the apparatus, a rocker shaft for each set of bars arranged at each end of the frame, upstanding rocker arms on said shafts which support at their upper ends the bars of said screen structure, connecting links for operatively connecting the rocker shafts of each set of rocker bars, and means for rocking in opposite directions the shaft for each set of bars, whereby the bars of one set receive an upward and forward movement, while the bars of the other set receive a downward and rearward movement. 110

4. In apparatus of the character described, the combination with a fixed supporting structure, of a frame pivoted to said supporting structure and adapted to assume various inclined positions, means for raising and lowering the lower end of said frame, a screen structure on said frame made up of two sets of longitudinally extending bars, disposed in alternate arrangement across the apparatus, a rocker shaft for each set of bars arranged at each end of the frame and provided with spline keys, 120 125 130

upstanding rocker arms formed with aligning key-ways to receive said keys of the rocker shafts, and adapted to be adjusted longitudinally of said shafts and support at their upper ends the bars of said screen structure, connecting links for operating in unison the rocker arms of each set of bars,

and means for rocking in opposite directions the shafts for each set of bars whereby the bars of one set receive an upward and forward movement while the bars of the other set receive a downward and rearward movement.

FRANK JONES.
